US00D932125S

(12) **United States Design Patent** (10) Patent No.: **US D932,125 S**
Tomita (45) Date of Patent: **** Sep. 28, 2021**

(54) **SCRAPER**

(71) Applicant: **Kabushiki-Kaisha Tomitahamono**,
 Tsubame (JP)

(72) Inventor: **Hiroshi Tomita**, Tsubame (JP)

(73) Assignee: **KABUSHIKI-KAISHA**
TOMITAHAMONO, Tsubame (JP)

(**) Term: **15 Years**

(21) Appl. No.: **29/728,126**

(22) Filed: **Mar. 16, 2020**

(30) **Foreign Application Priority Data**

Nov. 6, 2019 (JP) 2019-024665

Primary Examiner — John R Yeh

(74) Attorney, Agent, or Firm — Birch, Stewart, Kolasch & Birch, LLP

(57) **CLAIM**

The ornamental design for a scraper, as shown and described.

DESCRIPTION

FIG. 1 is a front view showing my new design for a scraper;
 FIG. 2 is a back view thereof;
 FIG. 3 is a top plan view thereof;
 FIG. 4 is a bottom plan view thereof;
 FIG. 5 is a right side view thereof;
 FIG. 6 is a left side view thereof; and,
 FIG. 7 is a bottom, right perspective view thereof.
 The broken lines in the drawings depict portions of the scraper that form no part of the claimed design.

1 Claim, 5 Drawing Sheets
